By: Monday Clarke Carpenter Attest:

UNITED STATES PATENT OFFICE.

HEINRICH KOPPERS, OF ESSEN-RUHR, GERMANY, ASSIGNORS TO THE KOPPERS DEVELOPMENT CORPORATION, OF PITTSBURGH, PENNSYLVANIA, A CORPORATION OF PENNSYLVANIA.

COKE-OVEN-DOOR-OPERATING APPARATUS.

Application filed August 31, 1921, Serial No. 497,370, and in Germany November 19, 1920. Renewed October 29, 1927.

The invention relates to devices for operating the doors of chamber ovens for producing gas and coke.

Ordinary coke oven doors are operated by tearing off the door upward from its seat and moving it out of its frame for the purpose of exposing the chamber opening. Door lifting devices have also been built in which the door is seized by a lever system and tangentially swung upward. This arrangement, however, has the disadvantage that the door is brought into positions other than those which it normally assumes during use. This results in exposing it on the one hand, to a greater extent to the effect of detrimental gases and vapors, and also in affecting the fireproof lining of the door.

The invention concerns a door lifting device for the customary coke oven doors lying flat in front of the chamber opening, and in particular for such as are made in accordance with the applicant's German Letters Patent 316,701, by means of which the door is also seized and swung by a lever mechanism. In order to make it possible, however, to retain permanently the vertical position of the door, the movement of the door is effected with the aid of a parallel link motion in such a way that the door is seized at two places by the lever mechanism and is then lifted upward parallel to itself and swung from out of the oven frame. Since in this arrangement the claws for lifting the door can be immediately brought into engagement with the door in the direction of the subsequent lifting movement, the claws can be used directly for releasing the door fastenings, by causing bolts rotatively attached to the door to be lifted out of their catches or strikes which are fastened to the oven frame.

In order to make the invention more clearly understood there are shown in the accompanying drawings means for carrying the same into practical effect, without limiting the invention to the details, which are illustrative and can be varied without departing from the invention. In said drawings—

Figure 1 is a side view of an oven door opener embodying the invention.

Fig. 2 is an end view of the same, showing also in vertical section the mouth of the oven and the door in place.

Fig. 3 is a plan view of the same.

Fig. 4 is a front view of the door.

On the frame *b* which is movable in front of the oven by means of motor *a*, the levers *dd* are supported for rotation or swinging movement in the frame *c*, these levers being connected with the arms *ee* and the couplings *ff* to form a parallel link motion. In the levers *dd* the supporting body or member *g* is rotatively arranged by means of spaced members associated with the supporting member *g* and has spaced claws or door engaging links or arms *hh* capable of engaging suitable ears or lugs *ii* in the door *k*. The upper lever arms or swinging means *d* are extended to form gears *l* which are engaged by the pinions *m* driven by the motor *n* through gearing. On the door *k* the trap-like bolts *oo* are arranged in such a way that they can pass crosswise behind strikes *pp* on the oven frame *qq*. Special cams *rr* of the bolts *o* project downward past the edge of the lugs or ears *i*. The support *g* is journaled in the levers *d* by means of eccentrics *s* in such a manner that it is possible to effect an adjustment with reference to the door, so that the exact setting of the distance can be made on the spot, this being made necessary according to the distance between the rails of the moving frame *b*, subject to slight variations, and the lugs *i*. Once properly adjusted, the eccentrics *s* are permanently set.

On swinging the support *g* upward from below, the claws or arms *hh* first strike under the cams *rr* of the bolts *oo* and unbolt the same. The claws or arms *hh* then engage the lugs or ears *ii* of the door *k* and, moving on, by means of the upward and circular movement of the levers *d* and as the supporting member *g* is provided with spaced members *z* that rotatably bear in the apertures *s* of the swinging means (levers *d*), which apertures are in the same vertical plane, the supporting member *d* is raised upward and outward and always is disposed in a vertical position by reason of the bearings sliding over the surface of the material around the apertures *s*. Such arrangement of mechanism will lift the door and swing it upward and outward without the door meanwhile leaving its vertical position because of the spaced member *z* being rotatably supported in the apertures *s* in the swinging means. The support *g* serves

as an intermediate element in order to smoothly carry out the necessary turning which would be impracticable at the places where the claws *hh* go into action. With the 5 door lifted and swung out of the oven frame *g*, the frame *b* and whole device can then be moved aside in order thus to completely expose the chamber opening. The closing is 10 accomplished in reverse order, in which operation, as soon as the claws *hh* are no longer in engagement with them, the bolts *oo* automatically drop into place again behind the strikes *p*.

What is claimed is—

- 15 1. A device for operating the doors of coke ovens having in combination: a supporting member; spaced arms thereon for engaging said doors; means for swinging said supporting member; spaced members 20 associated with said support for rotatably bearing in said swinging means.
2. A device for operating the doors of coke ovens having in combination: a plurality of arms engaging said doors; means 25 for lifting said arms, said arms being rotatably supported on said means.
3. A device for operating the doors of coke ovens having in combination: upper and lower operating levers; a supporting member 30 rotatably bearing in said levers; horizontally extended lifting arms carried by said supporting member and adapted to engage the upper and lower portions of the door.
- 35 4. A door operating device having in combination: upper and lower operating levers; eccentrics therein; a supporting member; means rotatably supporting said supporting member in said eccentrics; upper and lower 40 arms extending horizontally from said supporting member and carried thereby; said arms being adapted to hold said door in vertical position and against rotary movement.
- 45 5. A door operating device having in combination: spaced upper and lower operating levers; links connecting said levers, said links moving the lower lever upon rotation of the upper lever; the upper levers having

gears thereon; means engaging said gears for rotating said upper lever; a door supporting member rotatably bearing in said upper and lower levers; and means extending horizontally from said supporting member 55 for engagement with the door, said supporting member and said last mentioned means maintaining said door in vertical position during the operating movement.

6. In an oven door opener, the combination of upper and lower door-engaging devices adapted to removably engage the door, means for swinging said devices simultaneously on upward and outward arcs to break the door seal and remove the door from the oven, and means for maintaining the door 65 in vertical position during such operation.

7. In an oven door opener, the combination of upper and lower door-engaging devices adapted to removably grip the door, means for swinging said devices on upward 70 and outward arcs to remove the door from the oven, means for maintaining the door in vertical position during such operation, and means for adjusting the door-engaging devices inward and outward relative to the 75 swinging means and to the door-lugs for proper engagement with the latter preliminary to the removing operation.

8. In an oven door opener, the combination of upper and lower door-engaging devices, means for swinging said devices on upward and outward arcs to remove the door 80 from the oven, and means for maintaining the door in vertical position during such operation, said door-engaging devices having 85 means for releasing the door-bolts as they move to engage the door-lugs.

9. In an oven door opener, the combination of upper and lower door-engaging devices, means for swinging said devices on 90 upward and outward arcs to remove the door from the oven, and means for maintaining the door in vertical position during such operation, said swinging means comprising a parallel movement mechanism and eccentrics for forwardly and backwardly adjusting said door-engaging devices. 95

HEINRICH KOPPERS.
